UNITED STATES PATENT OFFICE.

ASAHEL B. T. MOORE, OF CEDAR RAPIDS, IOWA.

DESIGN FOR A BUTTON.

43,009.

Specification for Design. Patented Sept. 10, 1912.

Application filed May 20, 1912. Serial No. 698,634. Term of patent 14 years.

To all whom it may concern:

Be it known that I, ASAHEL B. T. MOORE, a citizen of the United States, residing at Cedar Rapids, in the county of Linn and State of Iowa, have invented a new, ornamental, and original Design for a Button, of which the following is a specification, reference being had to the accompanying drawing, forming a part thereof.

The figure is a plan view of the button showing my design.

I claim

An ornamental design for a button as shown.

ASAHEL B. T. MOORE.

Witnesses:

RUFUS RICKER,
B. L. WICK.
